UNITED STATES PATENT OFFICE.

FRANK A. HALLECK, OF MICHIGAN CITY, INDIANA, ASSIGNOR TO SULLIVAN MACHINERY COMPANY, A CORPORATION OF MASSACHUSETTS.

PIN EXTRACTOR FOR FORGING MACHINES.

Original application filed July 30, 1920, Serial No. 400,121. Divided and this application filed September 9, 1924. Serial No. 736,796.

This invention relates to forging machines.

It has for its object to provide an improved forging machine particularly one of a type adapted to operate upon hollow drill steels. In making or resharpening hollow drill steels the hollow portion is usually reduced due to the forging operation and in order to obtain a normal sized opening a pin is driven into the reduced hollow portion until the desired size opening is obtained. The pin will of course become wedged in the opening and in order to facilitate the removal thereof I have provided my improved means. In my present invention I use the usual clamping jaws of a drill steel forging machine in combination with a pivotal member adapted to grip the pin to move the same outwardly from the hollow portion of the steel when the collar or lug on the steel engages a fixed abutment.

In the accompanying drawings I have shown for purposes of illustration one form which my invention may assume in practice.

In these drawings,—
25 Fig. 1 is a front elevation of the usual type of forging machine.

Fig. 2 is a fragmentary vertical transverse section through the vise jaws showing the actuating rod therefor in elevation.

30 Fig. 3 is a vertical section on line 3—3 of Fig. 2.

In the illustrative form of my invention as disclosed in this application, which is a division of my copending application, Serial No. 400,121, filed July 30, 1920, I have shown the same as incorporated in a well known type of forging machine comprising a base 1 having an anvil 2 and a pneumatic swaging motor 3 adapted to cooperate therewith. Disposed to the rear of said swaging motor are the relatively movable vise jaws herein shown as comprising a stationary jaw 4 and a vertically movable jaw 5 actuated through rods 6 by any suitable power means. Usual attachments are mounted upon the vise jaws such as the gaging dies 7, clamping dies 8 adapted to cooperate with a suitable upsetting motor, and a pneumatically operated hole forming mechanism 9.

50 The attachment to the vise jaw to which this invention particularly has reference is for the removal of a hole forming tool after said tool is driven into the steel by the mecha-

nism 9. This improved pin or tool remover is clearly shown in Figs. 2 and 3 as comprising an opening 10 formed in the movable jaw while disposed therein is a suitable pin engaging device 11. This device is pivoted, as at 12, to the movable jaw and has a stop shoulder 13 adapted to engage the transverse surface of the opening 10 against which it is held by a suitable spring pressed pin 14 projecting downwardly from an opening 15 formed in said jaw. It is to be noted that the pin seats within a recess 16 formed in the upper surface of the member 11. A downwardly projecting portion 17 has a bifurcated portion 18 forming a sharp pin engaging claw 19 while the extremities of the two side portions of the bifurcated part are rounded as at 20 to act as a cam member upon engaging the surface 21 of the stationary jaw.

In the operation of the device, it will be assumed that the pin has been driven into the hole of the steel which will have either lugs 22 or a suitable collar thereon adapted to abut the front edge of the stationary jaw 4. The pin will be inserted by suitable manipulation of the steel within the bifurcation 18. The upper jaw will then be moved downwardly, whereupon the claw 19 will engage the pin and upon continuous downward movement of said jaw will tend either to bite into the pin or tightly grip the same, whereupon the pin will be forced outwardly by means of a toggle action due to pivotal movement of the member 11 about its axis 12. Obviously the rounded surface 20 will prevent the claw 19 from biting into the pin too far and will also assist in causing the member 11 to swing about its pivot.

While I have in this application specifically described one form which my invention may assume in practice, it is to be understood that this form of the same is shown for purposes of illustration and that the invention may be modified and embodied in various other forms without departing from its spirit or the scope of the appended claims.

What I claim as new and desire to secure by Letters Patent is:

1. Mechanism for removing a pin from a hollow drill steel comprising a movable member, a gripping means pivotally supported and actuated thereby for engaging one of the elements to be separated, and means for guid-

ing the said movable member to move in a direction transversely of the longitudinal axis of the member being gripped.

5 2. Mechanism for removing a pin from a hollow drill steel comprising relatively movable members, means for engaging a pin to cause removal thereof comprising a member pivoted to one of said relatively movable members and having a pin gripping arm, the 10 pivotal point of said member being offset from the point at which said pin is engaged.

15 3. A mechanism for removing a pin from a hollow drill steel comprising means for engaging one of said elements, and a member presenting a surface opposed to said engaging means, the latter being movable in one direction until said engagement, and then upon engagement automatically having different movement to cause removal of said pin.

20 4. In a forging machine, a pin extractor comprising a member reciprocable at an angle to the pin, a claw pivoted to said reciprocable member, the free end of said claw being adapted to engage a pin, said claw being 25 adapted to change its angle with respect to the pin which it engages upon reciprocation of said reciprocable member.

30 5. In a forging machine, a pin extractor comprising a reciprocable member, a member pivoted adjacent one end to said first mentioned member and adapted to engage a pin with its free end, movement of said reciprocable member being adapted to decrease the angle between said pivoted member and the pin.

35 6. In a forging machine, a reciprocable member, a member pivoted thereon between its extremities upon a pivot transverse to the direction of movement of said reciprocable member, means for holding said pivoted member in a predetermined normal position relative to said reciprocable member comprising a spring exerting pressure on said pivoted member to one side of its pivot to cause engagement between said pivoted member and said reciprocable member on the opposite side of said pivot, said pivoted member having a pin gripping means arranged at its forward end and being adapted to grip a pin and cause longitudinal movement thereof by means of a toggle action about its pivot.

45 7. Mechanism for removing a pin element from a hollow drill steel comprising means

against which one of them abuts to prevent movement thereof, a member reciprocable at an angle to said drill steel, and means carried by said reciprocable member for gripping and moving the other.

55 8. Mechanism for removing a pin from a hollow drill steel comprising means against which one of them abuts to prevent movement thereof, a member reciprocable at an angle to said drill steel, and means carried by said reciprocable member for gripping the other, and means whereby the gripping action of said gripping means is proportional to the resistance to movement of said reciprocable member.

60 9. Pin pulling mechanism comprising a reciprocating member, a pin gripping member pivoted thereto, a member presenting a surface for receiving the pin, and means carried by said gripping member for engaging the pin on movement of said reciprocating member for moving said pin on reciprocation of said member.

65 10. Pin pulling mechanism comprising a reciprocating member, a pin gripping member pivoted thereto, a member presenting a surface for receiving the pin, means carried by said gripping member for engaging the pin on movement of said reciprocating member, and other means carried by said gripping member adapted to engage said surface for causing movement of said gripping means 75 in a direction parallel to said surface for moving said pin on reciprocation of said member.

70 11. Pin pulling mechanism comprising an abutment member for the pin, a member reciprocable relative thereto, and a pin engaging device movably connected to one of said members and adapted to engage said pin and exert a pull upon the same upon relative reciprocable movement of said members.

75 12. Pin pulling mechanism comprising an abutment member for the pin, a member reciprocable relative thereto, a pin engaging device movably connected to one of said members and adapted to engage said pin and exert a pull upon the same upon relative reciprocable movement of said members, and yielding means for normally holding said device in pin engaging position.

In testimony whereof I affix my signature.
FRANK A. HALLECK.
